DECORATIVE MOLDING STRIP

Leland George Stone, Mundelein, Ill., assignor to
Amerock Corporation, Rockford, Ill., a corpora-
tion of Connecticut

Filed Feb. 9, 1967, Ser. No. 5,744

Term of patent 14 years

(Cl. D13—6)

FIGURE 1 is a front view of an end section of the decorative molding strip it being understood that the design repeats as indicated.

FIG. 2 is a top view of the strip.

FIG. 3 is a bottom view of the strip.

FIG. 4 is a side view as seen from the left in FIG. 1.

FIG. 5 is an enlarged sectional view taken along the line 5—5 in FIG. 1.

FIG. 6 is an enlarged sectional view taken along the line 6—6 in FIG. 1.

FIG. 7 is an enlarged sectional view taken along the line 7—7 in FIG. 1.

I claim:

The ornamental design for a decorative molding strip, as shown and described.
